SPECIFICATION forming part of **Design No. 20,511**, dated February 10, 1891.

Application filed January 15, 1891. Serial No. 377,894. Term of patent 14 years.

To all whom it may concern:

Be it known that I, LOUIS E. STILZ, a citizen of the United States, residing in the city and county of Philadelphia, State of Pennsylvania, have invented and produced a new and original Design for a Badge, of which the following is a specification, reference being had to the accompanying drawing, forming part thereof.

10 The leading feature of my design for a badge is an eight-pointed star and a seal with a castle and a knight thereon.

In the drawing, A designates the top bar of the badge, the same being of the form of

15 an eagle and a curtain depending therefrom.

B designates the ribbon, and C the bottom bar. Suspended from the bar C is an eight-pointed star D, on the face of which is the seal E, containing the castle F, the knight G, and the encircling chain H.

I claim—

A design for a badge, substantially as shown and described.

LOUIS E. STILZ.
